A. C. CURRIER.
SHOT PROOF DOME OR CUPOLA.

No. 36,896.

Patented Nov. 11, 1862.

UNITED STATES PATENT OFFICE.

ALEXANDER C. CURRIER, OF HALLOWELL, MAINE.

IMPROVED SHOT-PROOF DOME OR CUPOLA.

Specification forming part of Letters Patent No. 36,896, dated November 11, 1862.

To all whom it may concern:

Be it known that I, ALEXANDER C. CURRIER, of Hallowell, in the county of Kennebec and State of Maine, have invented new and useful Improvements in Shot-Proof Cupolas or Domes for Sea and Land Service; and I do hereby declare that the following is a full and exact description thereof, reference being had to the drawings accompanying this declaration, and to the letters, figures, and marks of reference in said drawings set down, making a part of this specification.

The nature of my invention consists in the shape, arrangement, and construction of the interior and exterior of such domes or cupolas and their appendages:

First. In the shape of the same, in that said shape is in part a segment of a sphere, spheroid, or of a polygonal body, but always in effect preserving the dome or cupola form. I flatten the top portion, which receives and accommodates a wheel set flatwise into the structure and making a part of the same. This wheel is convex outward—which is to say, upward. This wheel, or rather a circular concave and convex plate of iron fitting as a cover to said wheel, is perforated with holes, through which may run tubes designed and calculated, in connection with other arrangements, hereinafter to be described, to promote the ventilation of such domes or cupolas.

Second. In setting the base of such dome or cupola into the vessel below the plane of the top of the bulwarks or glacis, whereby said base and the lower portion of the dome and the contents of such lower portion are protected by the bulwarks or glacis from the enemy's shot; and, further, in such manner that the dome or cupola, being raised by proper gearing from its working bearings and thus presenting a larger circumference of the spheroid or other body at the plane of intersection with the bulwark, is made, by the intervention of a packing of rubber or other compressible substance, to tightly close the crevice between the dome and bulwark, effectually excluding water. In like manner such raising of the dome will throw out of the crevice at the intersection of the dome with the top of the bulwark any substances calculated to impede the rotation or working of such dome which may by accident or design have gotten into the

same. It will be understood that in the accompanying drawings the dome rests upon special timbers, which, if they were planked over, might be denominated a "special deck." In Figure 1 of the drawings one of these timbers is shown, (marked U U U.) These timbers sit about three feet (more or less) below the plane of intersection of the dome with the top of the bulwark. In such a vessel as is represented it is assumed that the main deck would come on a line with the top of the bulwark, as represented, and such deck or "roof," as it may be called, be plated over with iron more or less thick. Into such deck, on a vessel such as is represented, I would sink the dome some three feet; but it is not intended to confine the use of the dome to vessels of such description, or, indeed, to any vessel, or to make such sinking of the dome an indispensable condition of its use.

Third. In a grated flooring to such dome opening into the hold of the vessel, thus assisting in the ventilation of the dome, and, moreover, increasing the volume of air to be operated upon by violent sounds within or without the dome, and so mitigating the reverberation.

Fourth. In lining (on or against the inner surface of the dome) with rubber or some like medium to receive and dissipate the blows of sound.

Fifth. In providing in the top of the dome a ceiling parallel, or substantially so, to the floor, made of light wooden boards or other like substance, and having between that and the exterior structure layers of felt, tan, sawdust, or other like substance or substances fit to deaden the sound, making in such ceiling one or more recesses more or less shallow, the more effectually to break and dissipate the waves of sound and prevent reverberation.

Sixth. In closing the port-holes of such cupola or dome with a bar having an area at its outboard extremity sufficient for the purpose, and for lightness tapering to the inboard end, or otherwise constructed. This bar is placed between the rails of the ways or chassis on which the gun works. When the gun is run out, the bar rests on the floor of the dome. When the gun is run back by its own recoil or otherwise, the bar, hoisted by a tackle or other device, lies at an angle of twenty degrees,

(more or less) according to the height of the port-hole from the floor, the inboard end resting squarely against a foot-piece fixed securely between said rails, and the outboard end, closing the port-hole, resting against the inner surface of the dome and fitting as to its edges into a heavy flange, which keeps it in its place, while at the same time such flange gives strength to the structure of the dome at the point where it were otherwise weakened by the perforation for the port-hole.

Seventh. In providing a smaller aperture, closed inside by a gate and stopple, for taking an outlook, letting in light, or shooting through with small arms.

Eighth. In providing a cylinder or other form of receptacle around and parallel to the central shaft, forming an air-drum, from which air from without the vessel, pumped or forced in by a blower or other contrivance, may be driven into the dome through apertures in the central part of the floor. This cylinder or other receptacle is permanently fixed. To provide for the ease of the dome being raised from its working bearings, a corresponding cylinder or other receptacle, fitting either around or into the one last described, is made, and may be fastened to the bottom of the floor-work of the dome, sliding telescopically when the dome is raised, thus securing the continuity of cylinder to contain the air which may be pumped or forced in.

Ninth. In providing a screw with capstan-head for raising the dome, in which capstan-head a socket receives the said central shaft, and to said screw a nut resting on, clasping, and bolted to the keelson.

To enable others skilled in the art to make and use my invention, I will proceed to describe its construction and operation.

Referring to the foregoing and to the drawings accompanying this, I make in the top of the dome a wheel frame-work of whatever sufficient material the position requires. Of this frame-work; A, Fig. 1, denotes the hub; B B, the spokes, and C C the felly. I cover this wheel with a circular concave plate, of iron or other like substance, D, Fig. 1. I make a stout heavy rim or flange, E E, Fig. 1, of iron or other metal, annular between the ends of the ribs or plates of the main portion of the dome and the wheel aforesaid, fitting it on the one side to receive said ribs, and on the other to receive said felly, C C, Fig. 1. In the top of the dome I place a board ceiling, the outline of which, F F, is sufficiently indicated in the section drawings, Fig. 1. Between this and the wheel frame-work above described I put, G G, felting, tan, or other like substance. The inside of the dome I line throughout with rubber or other like material, H H H, Fig. 1, of sufficient thickness, fastening the same, as may be convenient, not too firmly or closely to the structure of the dome. I make apertures, i i i, Fig. 1, in the top of the dome for ventilation. These, running vertically or at an angle, it were well to fit with tubes,

whose mouths may flare downward where they come through the board ceiling. To further facilitate the ventilation, it were well to increase the areas of these apertures and tubes above the said mouths and again to diminish the same. For these tubes it is unnecessary to perforate much the frame-work wheel, as they may pass through A, and between B B and C C, and through F F, G G, and H H. The iron or other grating floor, J J, Figs. 1 and 2, I make of sufficient strength and proper material for the purpose for which it is to be used. Chassis or ways, K K, Fig. 1, are to be made, on which the guns may run, the rails and ties of which may be of iron or any suitable material; pierce the dome with one or more gun-ports, L, Fig. 1, which may be of the form of an ellipse, the smaller diameter of which will be little more than the diameter of the gun at the muzzle, and the larger diameter sufficient to allow the required elevation and depression. The gun-ports I close with a bar, M, Fig. 1, hereto fore substantially described, the inboard end of which rests, when the port is closed, against a foot-piece, N, Fig. 1, bolted to floor of dome between the rails of the chassis. The outboard end closing the port-hole is made to fit into a heavy flange or rim, O O O, Fig. 1, around the port-hole. (on the inside.) Tackle for raising the bar is indicated, P P, on Fig. 1. I make a small port, Q, Fig. 1, for letting in the light, to look out at, or to shoot small arms from. This I close on the inside by a bar, gate, and stopple. The stopple, making a part of the gate, fits into the circumference of said small hole, but does not fill it quite to the outer surface. I put inside around the base of the dome heavy timbering R R, Fig. 1. I prefer to frame the floor in the form of a wheel, set slightly convex, of which, in Fig. 1, there is represented a flange, 1, a center, 2, a lower flange, 3, spokes 4 4, and felly 5.

In Fig. 2 observe a passage, 6, between the hold of the vessel and the dome.

The central shaft, on which the dome rests in whole or in part in its revolutions, is indicated, T, in Fig. 1.

Special timbers of a ship, on which the dome is supported, are marked U U on Fig. 1. I place a metal cylinder, V V, Fig. 1, around the central shaft, with a bottom, through which the shaft runs, fitting tightly around the shaft, to exclude the air; pump in by a blower or other contrivance air from without the vessel, which conduct by a tube, , Fig. 1, to the said cylinder by a hole through the bottom of the same. If it were not designed to raise the dome at times, the cover of such cylinder, or the bottom of the floor-work serving as the cover, might be considered as permanently fixed; but to provide for the contingency of such raising I fix into or around the above-described cylinder another like cylinder, the one fitting into or around the other tightly, sliding telescopically when the dome is raised and lowered. For the top or cover of this upper cylinder, the bottom of the floor-

work of the dome might serve; but if a special cover be made for it, fasten that to the bottom of the floor-work; pierce holes 6 6, Figs. 1 and 2, through which the air from the cylinder may reach the dome. Besides a bearing for its revolution on the central shaft, I also provide for the dome auxiliary bearings, trucks set into an annular bar of iron resting on the aforesaid special timbers, the end of which bar is marked X X, Fig. 1, near the circumference of the dome. I insert a heavy band of rubber or other compressible elastic substance in the deck, bulwark, or glacis all around the dome. The ends of this band of rubber are indicated by Y Y, Fig. 1. Under the central shaft I would provide, by screw or other device, for raising the dome when out of action, and sometimes, perhaps, when in action. The dome thus raised compresses the band of rubber fixed as above, and thus the crevice 7 7, Fig. 1, between the dome and the sides of the vessel is effectually closed.

In Fig. 1, Z Z merely indicate a stanchion of the vessel.

I would prefer, without, however, confining myself to such details of structure, to make the ribs or plates of the dome of one thickness of iron or other substance—say four to ten inches thick—running from base of dome to flange or rim E E, Fig. 1, and having on the inside, near the edge flanges, tongues or eyes set on contiguous pieces, so as to correspond with each other, through which I would run across the line of contact of the ribs or plates stout bolts, as indicated in section A B C D of Fig. 3. This, taken in connection with the wedge shape of the ribs or plates, (their edges being coincident with radii struck from the center of the floor of the dome,) and also in connection with the fastening by the rim E E, Fig. 1, at top and a like support at base, would everywhere present to any exterior force the strength of the arch form of construction, while the fastening within by bolts, as just described, would prevent the springing out of the plates or ribs; or, as another detail of fastening, the edges of the ribs or plates might be beveled to fit into each other at an angle more or less obtuse, as shown in section A I K G of Fig. 3; or, as a third mode of fastening, the edges of the ribs or plates might be made concave and convex, fitting into each, as shown in section B M L E of Fig. 3.

To raise the dome, I provide a cylinder, of iron or other material, of sufficient strength, on the lower portion of which I work a screw of suitable pitch. Such screw turns in a nut, which may rest on the keelson. I make flanges on the nut which clasp the keelson on either side. Through these flanges I bolt the nut to the keelson. This cylinder I place below and in a line with the central shaft, T, Fig. 1, of the dome.

To the cylinder a b, Fig. 1, I make a head, d d, Fig. 1, of sufficient thickness and strength, considerably larger than the cylinder-head,

with circular or hexagonal sides, flat or convex on top. In this circular or hexagonal side (or sides) I make sockets e, Fig. 1, to receive hand-spikes to work the capstan f g h k, Fig. 1, thus turning the screw b, Fig. 1, worked on the end of the cylinder a b, Fig. 1. In the center of said head I work a socket, n n, Fig. 1, concave to receive the convex foot of the central shaft, t, Fig. 1, of the dome, in which socket said shaft T t, Fig. 1, may work as the dome revolves.

To steady and prevent distortion of the cylinder a b, Fig. 1, on which is worked the screw b, Fig. 1, I make below the head f g h k, Fig. 1, and above the nut p p, Fig. 1, a heavy plate, of iron or other material, of sufficient thickness, as large as or larger than the nut, sitting flat q q, Fig. 1, with a hole in its center, **, Fig. 1, in which may revolve that portion of the cylinder a, Fig. 1, which has no screw worked upon it, such cylinder a, Fig. 1, fitting accurately and working closely therein. On the vertical sides of this plate of iron q q are flanges r r, Fig. 1, running down and fitting to two or more sides of the nut p p, Fig. 1. The same bolts which pass through the flanges y y, Fig. 1, of the nut also pass through and fasten the said flanges r r, Fig. 1, and consequently the plate of iron q q, Fig. 1, of which they make a part. It will be understood that the axis of this cylinder a b, Fig. 1, is a prolongation of the axis of the central shaft, T, Fig. 1.

The advantages of such construction are that in a dome such as described less surface is exposed to the enemy's shot, in proportion to the working area secured within the dome than in any shot-proof structure now in use; second, greater angles are presented to the enemy's shot, in whatever line falling, thus increasing the tendency to glance off harmless; third, much greater working area of floor is obtained with like weights of armor; fourth, the reverberation of sound and the consequent effect upon those within the dome is prevented; fifth, a lesser thickness of plates may be used, as the line of the enemy's fire can seldom be perpendicular to a vertical line drawn through the surface of the dome at the first point of impact, and thus substantially always the exterior of the dome will be sloping to the line of shot; sixth, the effectual closing of the port when the gun is not run out; seventh, the best form for stability and absolute strength—to wit, a segment not greater than a hemisphere—or a spheroid or other body, always preserving the dome-like form; eighth, thorough protection of the vessel from water which might come in from the bulwarks or glacis being washed by the waves of the sea; ninth, immunity from derangement of the working or rotation of the dome through obstructions placed in the crevice between it and the sides of the vessel; tenth, the resting of the dome when in action upon its full bearings, both at and near the periphery and at the center; eleventh, thorough ventilation of the dome

is secured—in fact, ventilation as effectual as on the gun-deck of an ordinary vessel—the dome itself acting as a ventilator to the hold of the vessel.

What I claim as my invention, and desire to secure by Letters Patent, is—

1. A shot-proof dome, substantially as and for the purposes described.

2. In combination with a dome of this character, the arrangement of rubber, boards, felt, tan, sawdust, or, in the place of either, other like material or materials for preventing the reverberation and mitigating the effect of sound, substantially as and for the purposes described.

3. The bar for closing the port-hole and the arrangement of the same, substantially as and for the purposes described.

4. The open floor for such dome, substantially as and for the purposes described.

5. In combination with the foregoing, the arrangement of cylinders or other form of receptacle to aid in supplying the dome with air from without, substantially as and for the purposes described.

6. The arrangement of rubber or other like material between the dome and sides of the

vessel to keep out water, substantially as and for the purposes described.

7. The arrangement of raising the dome to throw out any substances which might impede its working or rotation through friction at the point of intersection with the top of the bulk-wark, substantially as and for the purposes described.

8. Each and all of the several modes of fastening: first, by flanges on the inner side of the ribs or plates and bolts across; second, the beveling of the plates, the one inward and the adjoining one outward at an angle more or less obtuse; and, third, the making of the edges of said plates or ribs the one concave and the adjoining one convex on a circle smaller or greater to fit into each other, each substantially as and for the purposes described.

9. The arrangement of raising the dome by a screw or its equivalent, into the capstan-head of which is set the foot of the central shaft of the dome, substantially as and for the purposes described.

ALEXANDER C. CURRIER.
